ADVERTISING AND WARNING SIGN

Ranch S. Kimball, Salt Lake City, Utah

Application July 23, 1936, Serial No. 92,082

1 Claim. (Cl. 40—132)

My invention relates to signs which are illuminated by gas filled tubes carrying electrical energy or more particularly to neon filled tubes and has for its object to provide a new and efficient method or type of floor or side walk advertising or illumination.

A further object is to provide a side walk advertising sign which is made with glass bricks laid in the pavement or road bed and which are made of sufficiently heavy glass to allow for walking or even traffic to drive thereover, without breaking the glass but at the same time giving the desired message or warning to the pedestrian or driver.

15 A further object is to provide a new safety factor which consists of warnings set in the pavements or road beds which will warn the passing traffic of danger or to be cautious such a place being at railroad crossings or school zones or in 20 danger zones for night illumination to slow down road traffic or warn the driver that it is dangerous to drive fast or to tell him to stop for crossings or like places.

25 A still further object is to provide a side walk space for advertising which may be used by stores, merchants, theatre owners, etc., and which signs may be made so that the signs may be removed and changed as desired or so that different colors of glass bricks may be used in the 30 surface or different colors of lights used thereunder.

35 A still further object is to provide a new method of warnings or advertising in which the use of under foot surface is utilized for illuminated signs, warnings, etc.

These and other objects I accomplish with the device illustrated in the accompanying drawing in which similar numerals and letters of reference indicate like parts throughout the several views and as described in the specification forming a part of this application and pointed out in the appended claim.

In the drawing in which I have shown the device,

45 Figure 1 is a vertical section of a side walk having the neon-filled glass tubes mounted under the glass bricks to provide the suitable changeable signs.

Figure 2 is a section of a single type of side walk illumination or road bed illumination.

Figure 3 is a plan view of a crossing for rail roads showing the danger warnings illuminated.

Figure 4 is a perspective view of a form of the device in which each individual letter is formed 55 in a metal casing.

Figure 5 is a vertical section of the letter T shown in Figure 4 through the leg of the T.

This invention relates more particularly to the use of the new glass bricks which have been developed for house building and for the use of 5 utilizing heretofore waste floor or road space for any desired advertising or warnings. Heretofore the only road or side walk advertising or warnings have been painted on the surface and soon wear off, but with my invention, the setting 10 of the glass surface in the floor or road with the advertising or warnings set thereunder in suitable illuminated letters makes a permanent long wearing sign.

In the drawing of my application I have shown 15 the use of glass bricks A set onto suitable frame work 5 which in turn is set into an opening B in the pavement or floor. The opening B may be of any depth or may be the usual room under the side walk, but across the top of the room 20 I provide a platform 6 carrying the sign elements made of the glass tubes 8 and connections 9 formed into any desired shape or form and made for artistic effects or for wording of signs, warnings, etc.

The platform 6 is adapted to be removed and replaced with a different one, having other designs or wording thereon when, and as desired. The glass bricks may be set in a flexible rubber base 10 as shown in Figure 2 with a step cut 11 30 in the side wall 12 of the opening 13 into which the brick is being set. The chamber 14 carries the sign elements 15 set in a plate 16 which plate is carried on step 17 in the side walls 12 and the brick may be removed from above and then the 35 sign element removed without having to work from underneath as shown in Figure 1. This type of device shown in Figure 2 may be used for crossing signs or where there is no room under the side walk.

40 In Figure 3 the use of the sign is shown for a rail road crossing warning, in which the rail road tracks are shown as R, and the road bed as S. The cross signs set in the hard surface or cement are shown as 19, 20, and 21. The letters of the 45 signs are shown as 22 and 23 when said letters are made separate, as shown in Figures 4 and 5.

In Figures 4 and 5, I have shown a method of making a letter shaped metal receptacle of insert D made with the outer portion or base 25 the 50 form of the letter desired, said base being closed on the sides and bottom and having a glass brick 26 set in the upper portion thereof the same shape as the letter. Below this brick there is set 55

the gas filled tube 21 connected with suitable source of electricity by the contacts 28 which either extend out the bottom as shown or may be extended out the sides of the brick. Thus, any desired lettering may be set into the side walk or sign medium and connected together without the danger of the bricks of glass being broken, each one being set off from the next one by the metal and each one being protected when handling by the metal frame work.

Having thus described my invention I desire to secure by Letters Patent and claim:

In a device of the class described, the combination of separate containers set into a ground surface having a predetermined surface outline; 5 transparent covers formed in said containers; continuously formed illuminating elements the shape of the respective containers and arranged therein.

RANCH S. KIMBALL. 10
